Des 2494

Charles Husband of Taunton Mass.
Letters Patent No 2494 Dated Oct. 16th 1866.
Design for Paper hangings &c.

The Schedule referred to in these Letters Patent and making part of the same.

To all Persons to whom these Presents shall come:

Be it known that I, Charles Husband of Taunton, in the County of Bristol and State of Massachusetts, have invented or produced a new and ornamental Design, to be worked into, or printed or painted or otherwise fixed on paper, cloth or other material: and I do hereby declare such design to be fully described in the accompanying drawing.

The design in question consists of five ornamental characters or figures, framed and arranged as represented at A, B, B, B, and having a checkered ground, C, between them, such ground being of short lines arranged in squares and with four dots, at the junction of each four of the squares. Also a series of dots arranged in a circle and about a central dot, these last dots being placed within each of the squares, the whole being as shown in the drawing.

I claim the said design as shown and described.
